INVENTOR,
Clyde E. Clapper,
BY *Roy E. Hamilton*,
Attorney.

A bolt 48 passes through a hole 50 provided therefor in connecting bar 32, and through arcuately elongated slots 52 formed in side walls 40 of the clamp. These slots are centered on bolt 44, and permit the connecting bar to pivot through a limited arc on bolt 44. The connecting bar may be fixed relative to the clamps by tightening bolts 48. Clamp 36 is identical with clamp 34, except that it is relatively inverted and the channel portion 38 thereof fits around central rod 18 of the umbrella.

Thus by loosening bolts 44 and 48, the elevation of umbrella 10 may be varied simply by changing the angularity of bar 32 relative to the staff. Also the umbrella may be tilted to any desired angle from horizontal by loosening bolts 44 and pivoting clamps 34 or 36 relative to connecting bar 32. The elevation of the umbrella may of course be further adjusted by adjusting the clamps slidably up or down staff 30 or rod 18. When the bolts 44 and 48 are loosened, staff 30 and connecting bar 32 may be brought into approximate axial alignment with umbrella rod 18, as shown in Fig. 2, and hence the support does not interfere substantially with the normal folding of the umbrella as shown.

What I claim is:

1. In an umbrella support of the class described having a staff laterally offset from the central rod of an umbrella and a connecting bar extending between said staff and umbrella rod, a clamp member adapted to secure one end of said connecting bar to said staff, said clamp comprising a sheet of metal formed to substantially U-shape forming a channel adapted to fit slidably and rotatably on said staff and substantially parallel side walls extending outwardly from said staff, said side walls being adapted to receive the end portion of said connecting bar pivotally therebetween, means for drawing said side walls together whereby said staff and connecting bar are clamping gripped therebetween, and a similar clamp member whereby the opposite end of

said connecting bar is adjustably secured to said umbrella rod.

2. In an umbrella support of the class described having a staff laterally offset from the central rod of an umbrella and a connecting bar extending between said staff and umbrella rod, a clamp member adapted to secure one end of said connecting bar to said staff, said clamp comprising a sheet of metal formed to substantially U-shape forming a channel adapted to fit slidably and rotatably on said staff and substantially parallel side walls extending outwardly from said staff, said side walls being adapted to receive the end portion of said connecting bar therebetween, a first bolt extending between said side walls adjacent said staff for pivotally supporting said connecting bar adjacent its end, a second bolt extending through said connecting bar in spaced relation to said first bolt and through arcuately elongated slots formed in said side walls and centered on said first bolt, whereby when said bolts are tightened said side walls will be drawn together to clampingly engage said staff and said connecting bar therebetween, and a similar clamp member adapted to secure the opposite end of said connecting bar to said umbrella rod.

CLYDE E. CLAPPER.
